UNITED STATES PATENT OFFICE.

WILLIAM T. SHRYOCK, OF ALLEGHENY, PENNSYLVANIA.

BRAKE FOR STREET-CARS.

SPECIFICATION forming part of Letters Patent No. 688,710, dated October 1, 1901.

Application filed August 8, 1900. Serial No. 26,303. (No model.)

To all whom it may concern:

Be it known that I, WILLIAM T. SHRYOCK, a citizen of the United States of America, residing at Allegheny, in the county of Allegheny 5 and State of Pennsylvania, have invented certain new and useful Improvements in Brakes for Street-Cars, of which the following is a specification, reference being had therein to the accompanying drawings.

10 This invention relates to certain new and useful improvements in car-brakes, and relates particularly to car-brake equalizers, and has for its object to provide means whereby the brake-shoes may be applied under equal 15 pressure to each wheel of the truck.

The invention further aims to construct a brake of this character whereby the equalizer may be adjusted at the will of the operator, together with various details of construction, 20 as will be hereinafter more specifically described and then particularly pointed out in the claims.

In describing the invention in detail reference is had to the accompanying drawings, 25 forming a part of this specification, and wherein like numerals of reference will be employed for designating like parts throughout the several views, in which—

Figure 1 is a longitudinal sectional view 30 through a part of a car-truck, showing a part of the car and my improved brake in position with the connecting-rods removed. Fig. 2 is a top plan view of a part of a car-truck with my improved car-brake equalizer in position. Fig. 3 is a detail perspective view of the equalizing-lever. Fig. 4 is a detail sectional view showing the manner of suspending the brake-shoes. Fig. 5 is a detail view of a part of one of the brake-beams and main 35 lever with the brake-shoe in section. Fig. 6 is a perspective view of my improved brake detached from the track, also showing the equalizing-levers.

In the operation of car-brakes actuated by 40 a main lever the efficiency of the brakes is affected in case the main lever becomes sprung or when the brake-shoes become worn, particularly in the type of brake employed, which is that generally known as the "Hubbard" 45 type. This application should be considered in connection with my former patent, No.

634,704, in which the objects of my invention were to shift the fulcrum-point of the active main lever against the forward pair of wheels, while in the present application the braking 55 stress upon the rear pair of wheels is graduated between a maximum and minimum and equalization of pressure against both the front and rear pairs of wheels is made possible, and this at the pleasure of the operator. 60

In the accompanying drawings, 1 indicates the front cross-bar of the truck, upon which the equalizing-lever 2 is pivotally supported, this lever being shown in detail in Fig. 3 of the drawings, being fulcrumed at or about its 65 center and provided on its one end with a wedge-shaped block 3 and having its other end bifurcated, as at 4, to receive and have secured therein the one end of the draft-rod 5. The other end of this draft-rod 5 is connected to a bell-crank 6, held supported in a bracket 7 from the underneath face of the car body or platform, said bell-crank having its other arm connected to a rack-lever 8, extending up through the car-platform. This 70 rack-lever 8, bell-crank, and the draft-rod just described regulate the position of the wedge-block 3, as it will be observed that by forcing the rack-lever 8 downwardly the horizontal arm of the bell-crank is depressed 75 at its outer end and the vertical arm thereof is moved forwardly in the direction the car is moving, moving the draft-rod in the same direction, together with the end 4 of the equalizing-lever, and moving the wedge-block 3 80 rearwardly of the direction in which the car is moving, the objects of which will be hereinafter further dwelt upon. Suspended from the underneath face of the car-body or upon and in front of the cross-bar 1 of the 85 truck is a grip-horn 9, on which is suspended a horizontal lever 10, which being suspended from its center has its one end connected to a thrust-arm 11, both ends of which are bifurcated, one end connecting with the lever 90 10 and the other end with the gooseneck main lever 12. The other end of the lever 10 is connected to a short draft-rod 14, having mounted in its free end a pulley 15. The 95 brake-chain 16 is connected to the spindle 100 of the brake-staff 17 and passes over the pulley 15, being returned forwardly toward

the brake-staff, with the other end thereof connected to an auxiliary draft-rod 18, operating through a bracket 19, suspended from the underneath face of the car-platform, and 5 on its forward end this auxiliary draft-rod 18 carries a nut and washer 20 and has arranged between the washer and the bracket a resistance-spring 21.

It will of course be understood that two 10 main levers are employed, one for each end of the truck, and in practice one of these levers is generally termed the "dormant" lever and the other the "active" lever. In the showing herein made in Figs. 1 and 2 but one of 15 the levers is illustrated, and we assume that the same is the dormant one, and, as herein shown, this lever is resting upon the wedge-block of the equalizing-lever 2. This main lever, which is of the gooseneck form, is 20 adapted to receive the brake-beam 22 at a point near the lower end of the lever, this beam being provided on its ends, as in general practice, with gudgeons 23 to receive the brake-shoes 24. In Fig. 4 I show how these 25 brake-shoes are suspended by a hanger 25 from the truck, which is the general form of construction. This hanger is pivotally attached to the brake-shoe or to the shoe-back at its lower end, and at its upper end is pivotally attached to the truck. In some instances, however, what is known as the 30 "elastic" hanger is employed, which could be used in connection with my construction of brake, or these hangers may be of other 35 form of construction than that I have shown and described, as the particular construction of these hangers is not essential to the operation of my brake. At its lower end the gooseneck or main lever carries a short arm 40 26, which is pivotally connected by the connecting-rod 27 to a hanger 27', carried by the front brake-beam. In the present illustration, the gooseneck being applied adjacent to the rear right-hand wheel, the connecting- 45 rod 27 connects with the hanger 27' on the front brake-beam adjacent to the right-hand front wheel, and the active gooseneck or main lever, which is applied adjacent to the left-hand front wheel, connects with a hanger 50 28' on the rear brake-beam adjacent to the left-hand rear wheel, these hangers 27' 28' on each brake-beam corresponding to the short arms 26, carried by the two goosenecks or main levers, which principle will be readily 55 understood.

In operation the active lever, it will be understood, is the one at the front of the truck—that is, the lever at the front in the direction the truck is moving. The equalizing-lever 2 60 is moved by the rack 8, bell-crank 6, and draft-rod 5, so that the wedge-block 3 is moved from under the top of said lever and the latter rests in its normal position on top of the cross-bar 1, the arc travel of such lever being, of course, greater when in this normal position than when the wedge-block is in 65 under the lever. At the same time the dor-

mant lever has the wedge-block in under the same, holding the short arm 26 of the dormant lever more nearly in the vertical line 70 or approaching a right angle with reference to the connecting-rod 27, bringing a greater braking stress against the rear wheels. The arc travel of point at which the connecting-rod 27 is attached to the short arm 29 of the 75 active lever is longer when the top end of said lever lies in its normal position than when the wedge is placed under or against it, because the changing of that point of bearing varies the distance between two extreme 80 points of efficiency in the said lever. To illustrate this clearly, I have drawn an imaginary line 28 from the central line of the rear brake-beam to the point of contact of the connecting-rod 27 at the hanger of the front 85 brake-beam. The shifting of point 29 with reference to this line 28 increases or decreases the pressure at the wheel, the wedge shape of the block 3 providing for this graduation of the position of the short arm 26. 90

It will be observed that in the construction of brake shown and described the brake-shoes of the front brake-beam are drawn under the wheel, but in the same direction in which the wheel is moving, having the effect of drawing the pins and gudgeons for connecting up the brake through the lost motion to a bearing and holding the same at this point until the strain on the draft-rod is released. This will be evident, because the long end of the lever 100 to which the draft-rod is attached is over the front brake-beam, while on the rear brake-beam the arms to which the connecting-rods are attached are under the beam and the effect is directly contrary to that of the front 105 beam, having an upward tendency, or in the same direction in which the wheels are turning. Therefore when draft is made upon the long end of the main lever and through the agency of the connecting-rods all pins and 110 gudgeons used in the connections are drawn through the lost motion and held to a bearing, thereby preventing climbing or bucking of the shoes, which is common where two opposite forces are employed for actuating the 115 brakes.

The equalizing-lever at the front of the car, or, in other words, the lever at the end of the car in the direction in which said car is moving, is always disengaged or removed from in 120 under the main lever, while the equalizing-lever at the rear end of the car is at such time engaged under the main lever. The main lever therefore at the front of the car is the acting active lever and the main lever at the 125 rear of the car is the acting dormant lever, the lever at the front of the car always being the acting active lever and the one at the rear of the car always being the acting dormant lever. The showing in Fig. 1 illustrates the 130 acting dormant lever, the lever at the opposite end of the car (not shown) being the acting active one, or, in other words, the car as shown in Fig. 1 is moving to the left.

It will be noted that various changes may be made in the details of construction without departing from the general spirit of my invention.

5 Having thus fully described my invention, what I claim as new, and desire to secure by Letters Patent, is—

1. In a car-brake, the combination with the brake-beams, each having a hanger, a goose-neck main lever connected to each brake-beam and provided with a hanger corresponding to the hanger on each brake-beam, and connecting-rods attached at one end to the hanger of the main lever and at the other end to the 10 hanger carried by the brake-beam, of an equalizing-lever supported from the car-truck and adjustably engaging the upper end of the main lever for varying the position of said dormant main lever.

2. In a car-brake, the combination with the brake-beams, and the rods connecting said beams, of a main lever connected to each beam, the lever connected to one beam being dormant when the lever connected to the other 20 beam is active, and an equalizing-lever carrying means for engagement with the dormant lever for varying the position of said dormant lever, substantially as described.

3. In a car-brake, the brake-beams and the 30 rods connecting said beams, combined with a main lever connected to each beam, the lever connected to one beam being dormant when the lever connected to the opposite beam is active, an equalizing-lever for each main 35 lever, and means for adjusting the position of said levers whereby the position of the dormant main lever may be varied, substantially as described.

4. In a car-brake, the combination with the 40 brake-beams, the shoes carried thereby, and the rods connecting said beams, of a main lever connected to each brake-beam, means connected to each main lever for operating the same, an equalizing-lever for each main 45 lever, one of said main levers being dormant when the other is active, the equalizing-lever for the dormant lever being in engagement therewith and the equalizing-lever for the active lever being out of engagement with said 50 lever during the time it remains as the active lever, substantially as described.

5. In a car-brake, the combination with the 55 brake-beams, the shoes carried thereby, and the rods connecting said beams, of a main lever connected to each brake-beam, one of said levers being dormant when the other is active, means for operating the levers, and an equalizing-lever for each main lever, the equalizing-lever for the dormant main lever 60 being in engagement with the said dormant main lever, and the equalizing-lever for the

acting active lever being out of engagement therewith, substantially as described.

6. In car-brakes, two main operating-levers adapted to be operated independently and 65 one of which is adapted to remain dormant when the other is active, combined with an equalizing-lever for each main lever, the equalizing-lever for the dormant main lever being in engagement therewith when the said 70 lever is acting as the dormant main lever, and the equalizing-lever for the acting main lever being out of engagement therewith.

7. In car-brakes, two main operating-levers adapted to be operated independently and 75 one of which is adapted to remain dormant when the other is active, combined with an equalizing-lever for each main lever, the one equalizing-lever adapted to graduate the position of the acting dormant main lever by 80 engagement with said dormant main lever, and the other equalizing-lever being out of engagement with the acting active main lever, substantially as described.

8. In a car-brake, the combination with the 85 brake-beams and the brake-shoes, of rods connecting the brake-beams and adapted when the brake-shoes are applied to move in the direction the truck is moving, a main lever connected to each brake-beam for operating the 90 same, one of said levers being dormant during the time the other is serving as the active lever, and an equalizing-lever for each main lever, the equalizing-lever for the acting dormant main lever being in engagement with 95 the said dormant main lever, and the equalizing-lever for the acting active lever being out of engagement therewith, substantially as described.

9. In a car-brake, the combination with the 100 brake-beams and brake-shoes, of rods connecting the brake-beams and adapted when the brake-shoes are applied to move in the same direction as the truck is moving, a main lever connected to each brake-beam, one of said 105 levers being normally active and the other normally dormant, the active lever when actuated moving in the opposite direction to that in which the truck is moving, and an equalizing-lever for each main lever, the 110 equalizing-lever for the acting dormant main lever being in engagement therewith, and the equalizing-lever for the acting active main lever being out of engagement with said active lever, substantially as described. 115

In testimony whereof I affix my signature in the presence of two witnesses.
